WIRE TYING MACHINE AND METHOD

Ivan H. Spoor, Berwyn, Ill., assignor to The Gerrard Company, Inc., Chicago, Ill., a corporation of Delaware

Application August 29, 1929, Serial No. 389,115

12 Claims. (Cl. 140—93)

This invention has to do with wire tying machines of the type with which a wire looped about an object or group of objects may be tensioned and twisted and the surplus ends of the wire then 5 cut off.

One object of the invention is to provide, in a machine of the type described, an improved arrangement of the tensioning mechanism which permits coil wire to be used with a minimum 10 amount of waste and leaves the cut end of the wire leading to the coil in good condition ready for the next tying operation.

Another object is to provide an improved construction within the winding head of the tensioning mechanism which prevents the end of the 15 wire inserted therein from slipping out.

Still another object is to provide an improved gripper which engages the wire automatically, holds the wire firmly, and may be adjusted a number 20 of times to present different gripping surfaces as the surface last used becomes worn.

Still another object is to provide an improved organization of the tensioning mechanism which permits both the winding head and the gripper 25 to be readily assembled and attached as complete units.

Still another object is to provide an improved arrangement in which the detachable brackets carrying the winding head and the gripper also 30 serve to hold the guides and the cutters against removal.

Still another object is to provide an improved cutting mechanism in which the knives are double ended and are readily reversible end for 35 end with respect to the knife carriers.

Still another object is to provide an improved organization of parts in the cutting mechanism whereby the cutters are actuated through adjustably positioned pins which permit the cutting operation to take place at different times with respect to the completion of the twisting operation.

A further object of the invention is to provide an improved method of tying objects with wire taken from a coil.

45 Other objects and advantages of the invention will be apparent to those skilled in the art upon a full understanding of the improved construction, arrangement and operation of various parts of the machine.

50 A wire tying machine which incorporates in one form or another all of the features of the invention, is presented herein for the purpose of exemplification, but it will of course be understood that the invention is susceptible of embodiment in other structurally modified forms coming equally

within the contemplated scope of the appended claims.

In the accompanying drawings:

Fig. 1 is a top view of the machine;

60

Fig. 2 is a front view of the same;

Fig. 3 is a right end view;

Fig. 4 is a vertical section, taken either on the line 4—4 of Fig. 1 or the line 4—4 of Fig. 2;

Fig. 5 is a section corresponding to Fig. 4, showing the position assumed by the cutting mechanism at the completion of the cutting operation;

Fig. 6 is a vertical section, taken on either the line 6—6 of Fig. 1 or the line 6—6 of Fig. 2;

Fig. 7 is a vertical section, taken on either the line 7—7 of Fig. 1 or the line 7—7 of Fig. 2;

70

Fig. 8 is a vertical section, taken on the line 8—8 of Fig. 1;

Fig. 9 is a horizontal section, taken on the line 9—9 of Fig. 2;

75

Fig. 10 is a perspective view of the wire-engaging element forming a part of the gripper at the right side of the machine; and

Fig. 11 is a top view of the tie which the machine produces.

The wire tying machine shown in the drawings 80 is adapted to be used in tying round wire about such objects as boxes, crates, bales, stacks, bundles, and the like. It may be used either with wire cut to length or with wire in coil form. In

preparing to operate the machine, when using 85 wire in coil form, the machine is placed on the box or other object and the end of the wire from the coil is inserted in any one of several radially extending slots 10 in the periphery of a winding head 11 located at the left side of the machine 90

(see Fig. 1). The head 11 is then rotated a little by means of a handle 12 in order to bend the wire slightly about the head whereby to effect a preliminary gripping engagement, and the portion of

the wire leading back to the coil on the right is 95 then pushed rearwardly into aligned slots 13, 14 and 15 which are formed respectively in a guide member 16, a twisting pinion 17 and another guide member 18 (see Fig. 2). The guide members 16

and 18, with the slots 13 and 15 therein, constitute 100 forked yokes. Upon leaving the slot 15 in the guide member 18, the wire is passed to the right beneath a thin lip 19, looped downwardly in a clockwise direction about the box, pushed rearwardly into the slots 13, 14 and 15 into lapped

parallel relation with the portion of the wire already occupying the rearmost portions of such slots, and then pushed rearwardly over the lip 19 beneath a beveled nose 20, which nose is thereby 105 caused to ride upwardly, carrying with it a cir-

110

cular peripherally serrated gripping disk 21 which, with the nose 20, is pivotally mounted at 22. As soon as the wire has been pushed far enough rearwardly on the lip 19 to clear the rear 5 edge of the nose 20, the disk 21 springs downwardly again into firm gripping engagement with the wire under the action of a spring 23.

The first operation of the machine, after the wire has been arranged in the manner above described, 10 is the tensioning of the wire, which is accomplished by rotating the head 11 in a clockwise direction with the hand lever 12. The next operation is the twisting together of the lapped parallel portions of the wire in the slots 13, 14 and 15, which is accomplished by rotating the pinion 17 with another hand lever 24 (see Fig. 7). The next and last operation is the cutting off of the surplus wire at opposite ends of the tie, which is accomplished by moving two knives 25 and 26 20 with a shearing action across the outer side faces of the guide members 16 and 18 with the hand lever 24 (see Figs. 4, 5 and 6).

The slots 13, 14 and 15, in which the lapped parallel portions of the wire are positioned during 25 the tensioning, twisting and cutting operations, are of ample depth to accommodate the lapped portions of the wire but are not wide enough to permit such portions to pass about each other, with the result that, when the pinion 17 is turned, 30 the portions of the wire positioned in the slot 14 in the pinion are caused to turn relative to the portions held in the slots 13 and 15, thereby producing a strong double twist.

The frame of the machine consists of a relatively thin flat laterally elongated base plate 27. The twisting and cutting mechanisms are mounted directly on the base, while the tensioning mechanism, which may be considered as including both the winding head 11 at the left side of 40 the machine and the gripping disk 21 at the right side, is mounted indirectly thereon (see Fig. 1), the head 11 being journaled on an L-shaped bracket 28 which is positioned on the base by dowel pins 29 and is held down against the same 45 by machine screws 30, and the gripping disk 21 being pivoted to another L-shaped bracket 31 which is rigidly secured to the base in the same readily detachable manner as the bracket 28.

The slotted periphery of the head 11 is centrally 50 grooved (see Fig. 1) to cause the wire in being wound about the head to center itself with respect thereto, and the axis of the head is positioned horizontally in rearwardly converging relation to the median plane of the twisting pinion 17, whereby 55 to urge the parallel lapped portions of the wire rearwardly in the slots 13, 14 and 15 during the tensioning operation and thereby insure correct positioning of such wire portions during the subsequently performed twisting and cutting operations. 60 The head 11 is journaled on the shank of a headed bolt 32 (see Fig. 9) which is carried by the bracket 28. A ratchet 33 is also journaled on the bolt 32 behind the head 11 and is connected with the head by dowel pins 34. The hand lever 65 12 used in rotating the head is pivotally mounted on the bolt 32 behind the ratchet 33 and carries a pivotally mounted downwardly spring-pressed pawl 35 (see Fig. 8) which engages with the teeth of the ratchet when the handle 12 is swung toward 70 the right, thereby causing the ratchet 33 and the head 11 to turn in a clockwise direction. The ratchet and the head are prevented from turning backwardly in an anti-clockwise direction by means of an upwardly spring-pressed plunger 36 75 which, like the pawl 35, engages with the teeth of

the ratchet. The front slotted and grooved portion of the head 11 is recessed and contains a radially flanged cap 37 which is fastened to the front end of the bolt 32 by means of a screw 38. The flanged portion of the cap is adapted to prevent the end of the wire from slipping forwardly out of the slot.

The gripping disk 21, which is located at the right side of the machine and is adapted to resist, 80 through the wire, the pulling action of the head 11, has associated therewith a sheet metal stamping 39 of which the beveled nose 20 forms one part. The stamping 39 has a rearwardly bent ear 40 under which the spring 23 is compressed and has another rearwardly bent ear 41 which extends into any one of four eccentrically formed holes 42 in the disk 21. A machine screw 43 which constitutes the pivot for the interlocked disk and stamping at the point 22, extends through an aperture in the stamping 39 into one of the holes adjoining the hole in which the locking ear 41 is positioned. The nose of the stamping 39 preferably extends to about the center of the disk 21, as shown in Fig. 3, thereby blanking off approximately one-half the width of the gripping edge of the latter. By removing the screw 43, the stamping may be separated from the disk and re-assembled again there-with in any one of four positions against either one side or the other of the same, with the result that any one of eight different adjustments of the 105 disk, presenting as many different edge sections to the wire, is possible. When the serrations at the rear side of the lowermost portion of the disk become worn, fresh serrations may be presented at that location by merely making an adjustment 110 in the manner above described. A finger piece 44 is formed on the bracket 31 behind and to the right of the gripper for affording a purchase for the hand of the operator in pushing the wire rearwardly beneath the beveled nose 20 of the 115 gripper.

The twisting pinion 17, which is positioned at the center of the front of the machine, is provided with hollow trunnions 45 and 46 which are journaled in the rearmost portion of a recess which is 120 formed between the base proper and a vertically spaced overhanging portion 47 thereof. The pinion is held against endwise movement by the side walls of a slot 48 which is formed in the overhanging portion of the base, and the trunnions 45 and 46 turn freely in bushings 49 and 50 which line the recess from the sides of the pinion to the guide members 16 and 18. The pinion meshes with a gear 51 which is keyed at 52 to a shaft 53, and the shaft 53 is journaled in two spaced ears 125 54 and 55 which extend upwardly from the base as integral portions thereof. The hand lever 24, which is used to rotate the pinion 17, is provided with bifurcated inner end portions 56 and 57 (see Fig. 1) which are journaled on the shaft 53 between the gear 51 and the supporting ears 54 and 55. Adjacent the periphery of the gear 51, the bifurcated portions of the hand lever are provided with spring-pressed plungers 58 and 59 which bear against the side faces of the gear and are 130 adapted to ride into recesses 60 formed at diametrically opposite points on the gear. The gear 51 is consequently rotated one-half of a revolution every time that the hand lever 24 is swung forwardly a full stroke through an angle of 180°. 135

In forming the particular tie shown in Fig. 11, three complete turns of the twisting pinion 17 are required, which turns are accomplished by two full strokes of the hand lever 24, the gear ratio being three to one. While the hand lever 24 is 140 145 150

being swung back from its foremost position to its rearmost position, the gear 51, together with the twisting pinion 17, is prevented from turning inadvertently in either direction by means of a spring-pressed indexing plunger 61 which is mounted in the base 27 and is adapted to ride into shallow recesses 62 formed at diametrically opposed points in one of the side faces of the gear 51.

The knives 25 and 26, which serve to cut the surplus wire from the tie, are mounted on the front edges of two carriers 63 and 64 (see Figs. 2, 4 and 6), which carriers are pivoted on pins 65 which extend through the guide members 16 and 18 into the base. The carriers are held against the guide members by laterally abutting surfaces on the brackets 28 and 31 and are normally maintained in raised inoperative positions by means of coil springs 66 beneath the lower edges of the same. The carriers are provided with headed pins 67 which are screwed into the carriers and project rearwardly from the upper portions thereof, being secured in any desired position of adjustment by means of lock nuts 68. The heads of the pins 67 are adapted to be engaged and forced forwardly by the action of pins 69 which are mounted eccentrically in collars 70 keyed to the ends of the shaft 53 beyond the ears 54 and 55. Upon each complete revolution of the shaft 53 resulting from two forward strokes of the hand lever 24, the knife carriers swing forwardly. The knives 25 and 26 are positioned on the carriers by dowel pins 71 and are fastened in place by screws 72. The knives are provided with cutting edges at both ends, and may be easily reversed to present a fresh cutting edge when the holding screws are removed. The knives are of different shapes—the knives 25 having a narrow cutting edge so as to cut only the portion of the wire which is in the back of the slot 13 in the guide member 16 (see Fig. 6), and the knife 26 having a relatively wide cutting edge and being forwardly spaced with respect to the front edge of the carrier 64 by the formation of a notch 73 in the carrier adjacent the bottom of the knife (see Fig. 4), which notch 45 serves to receive the portion of the wire in the back of the slot 15 in the guide 18 whereby to allow the knife to cut only the foremost portion extending to the gripper.

A noteworthy feature in the operation of the machine is the unique method of tying with wire taken from a coil positioned alongside the machine, without the usual waste of wire, and without the necessity of clipping the free end of the wire prior to the tying operation in order to present a satisfactory end for insertion in the machine. At the completion of each tying operation, the free end of the coil will be found under the gripper in a straight condition unaffected by the tying operation except for the presence of cross markings imprinted thereon near the end by the serrations on the surface of the gripper. The end of the wire under the gripper, when pulled to the right, will be released by the gripper and may be immediately inserted in one of the slots 60 in the winding head in preparation for the next tying operation. It is not necessary to clip off the wire to form a new end thereon, since the end taken from the gripper is not bent at all by reason of its engagement with the same and the 70 cross markings on the end are sufficiently close to the extremity to be on the subsequently cut off portion of the wire bent about the head in the course of the tensioning operation.

I claim:

75 1. In a machine for tying objects with wire

taken directly from a coil, the combination, with a twisting mechanism, of a tensioning mechanism consisting of a movable device at the left side of the twisting mechanism to which the free end of the wire from the coil is adapted to be attached, a stationary device at the right side of the twisting mechanism to which a portion of the wire leading back to the coil is adapted to be attached and held stationary after the wire has been looped about the object in a clockwise direction, and means for actuating the movable device to place the looped portion of the wire under tension.

2. In a wire tying machine, an eccentrically pivoted circular disk having a serrated periphery for gripping engagement with the wire, means for pressing the disk in one direction about its pivotal axis whereby to grip the wire, and means for changing the location of the pivotal axis of the disk with respect to some particular portion of the serrated periphery without disturbing the eccentricity whereby to present different portions of the serrated periphery to the wire.

3. In a wire tying machine, a peripherally serrated gripping disk having a plurality of apertures therein, a holder for the disk having a portion which is adapted to interlock with the disk in any one of the apertures, a pin positioned eccentrically with respect to the disk for pivotally mounting the disk and the holder as a unit in 105 any one of the different interlocked positions possible by reason of the multiplicity of apertures, and a spring acting against the holder to swing the disk about its pivotal axis into gripping engagement with a wire.

4. In a wire tying machine, a centrally recessed tensioning head having a radially and axially opening slot in which the end of the wire to be wound about the head is adapted to be inserted, and a member which is positioned in the recessed portion of the head and is provided with a flange for lateral abutment with the end of the wire in the slot.

5. In a wire tying machine, a substantially flat laterally elongated base plate, a twisting mechanism mounted on the plate intermediate the sides thereof, a pair of stationary brackets detachably secured to the plate in rigid association therewith at opposite sides of the twisting mechanism, and a tensioning head and gripper 125 mounted respectively on said brackets for application to or removal from the machine as units with the brackets.

6. In a wire tying machine, a substantially flat laterally elongated base, a twisting mechanism 130 mounted on the base intermediate the sides thereof, a pair of cutters pivotally mounted on the base at opposite sides of the twisting mechanism, a pair of brackets detachably secured to the base beyond the cutters in lateral abutment therewith for holding the cutters in position, and wire gripping and tensioning means mounted on said brackets and removable as units therewith.

7. In a wire tying machine, a forwardly projecting lip over which a portion of a wire to be gripped is adapted to be moved rearwardly, a pivoted dog above the rear portion of the lip for gripping the wire, and a forwardly projecting nose associated with the dog above the lip in rearwardly converging relation to the latter for automatically lifting the dog into a position to grip the wire when the latter is moved rearwardly on the lip.

8. In a wire tying machine, a pivotally mounted cutter, a rotatable member having an ec- 150

centric portion, a headed pin adjustably carried by the cutter for engagement with the eccentric portion of the rotatable member whereby to oscillate the cutter to any desired extent upon rotation of the member, and means for rotating the member through a complete revolution during each tying operation of the machine.

5. In a wire tying machine, a slotted wire-holding yoke, a knife carrier pivotally mounted against one side of the yoke, and a double-ended reversible knife detachably secured to the carrier for shearing coaction with the edge of the yoke at the location of the slot.

10. The method of tying objects with wire taken from a coil, which consists in withdrawing from the coil enough of the wire to form a loose loop about the object, forming such a loop without cutting the wire portion leading back to the coil, securing the free end of the wire in a movable tensioning device which in operation will deform a portion of the wire adjacent such end, securing the portion of the wire which leads back from the loop to the coil in a stationary holding device which will not deform the wire, moving the tensioning device to draw the wire tight about the object, twisting the overlapped wire portions to-

gether between the tensioning and holding devices, and cutting the wire free from the tensioning and holding devices between the latter and the twisted section, whereby to leave the coil with a newly cut undeformed end ready for use 80 without straightening or trimming in the next tying operation.

11. In a wire tying machine, a tensioning head having a laterally and outwardly opening slot in which the end of the wire to be wound about the 85 head is adapted to be inserted, and means within the head adjacent the center of the same for engagement with the tip only of the wire to prevent the wire from slipping laterally out of the slot.

12. In a wire tying machine, a wire gripping member having a plurality of optionally usable edge sections for gripping engagement with the wire, a pivot on which the member is eccentrically mounted, means for pressing the member in one direction about its pivotal axis whereby to cause one of the edge sections to grip the wire, and means for permitting the position of the member to be reversed on its pivot whereby to present a different edge section to the wire. 95
